UNITED STATES PATENT OFFICE.

GEORGE W. MOSBY, OF NEW YORK, N. Y.

DEVICE FOR HONING AND STROPPING RAZORS.

SPECIFICATION forming part of Letters Patent No. 759,626, dated May 10, 1904.

Application filed January 27, 1904. Serial No. 190,776. (No model.)

To all whom it may concern:

Be it known that I, GEORGE W. MOSBY, a citizen of the United States, residing at New York, in the county of New York and State 5 of New York, have invented new and useful Improvements in Devices for Honing and Stropping Razors, of which the following is a specification.

My invention relates to devices for honing and stropping razors and other edged implements; and its primary object is to provide simple and effective mechanism for producing the required oval or elliptical movement of a razor or other blade over a sharpening-surface.

A further object of the invention is to provide mechanism of novel construction so arranged with relation to a yieldingly-supported hone as to insure the movement of the 20 blade being sharpened over the entire surface of the hone, thereby avoiding undue wear upon the latter and the consequent formation of ridges or uneven places thereon.

A further object of the invention is to provide effective means for securing a uniform frictional contact between the blade and hone, thus avoiding uneven wear upon different portions of the sharpening-surface and equally distributing the weight or bearing contact 30 throughout the edge of the blade.

In addition to the general features above outlined the invention consists of the novel devices hereinafter described for guiding and cushioning the moving parts of the mechanism and for preventing the accidental displacement of the operating handle or lever while the razor or other implement is attached thereto.

The construction of the device will now be 40 specifically described in connection with the accompanying drawings, in which—

Figure 1 is a top plan view of the invention, showing a razor attached thereto in position for honing. Fig. 2 is a vertical section taken on the line 2 2 of Fig. 1. Fig. 3 is a detail section on the line 3 3 of Fig. 1. Fig. 4 is a section on the line 4 4 of Fig. 1. Fig. 5 is a top plan view of the vibrating plate constituting an element of the mechanism detached from the disk to which it is pivoted.

Fig. 6 is a transverse vertical section of said plate on the line 6 6 of Fig. 5. Fig. 7 is a detail perspective view illustrating the means for detachably securing the inner end of the operating-handle to the movable rod of the 55 device. Fig. 8 is a perspective view of one of the supporting-holders of the hone. Fig. 9 is a perspective view of one of the bracket-bearings of the hone-holders. Fig. 10 is a plan view of a modified embodiment of the invention adapted for the sharpening of safety-razors, and Fig. 11 is a section on the line 11 11 of Fig. 10.

The reference-numeral 1 designates a base serving as a support for the hone and operating mechanism and preferably provided with rubber feet or pegs 2. Obviously, however, a table or any other suitable support might be substituted for the base-board shown.

3 designates a disk pivotally supported upon 70 the base 1 by means of a bolt 4, extending centrally through the disk and through the base, the under surface of the latter being countersunk to accommodate a nut 5 for securing the bolt 4. A flanged wear-plate 6 is 75 interposed between the base and the disk 3, as best shown in Figs. 2 and 3.

The disk 3 is formed with a vertical opening 7 in rear of the center, through which extends a post 8, having a transversely-bored 80 head 9 to receive the rear end of a rod 10, a coil-spring 11 encircling said rod between the head 9 and a cross-pin 12, extending through the rod. To the opposite sides of the lower end of the post 8 are secured the inner ends 85 of coil-springs 13, said springs being located in a recess 14, formed in the upper surface of the base and having their outer ends secured to the adjacent end walls of the recess 14, Fig. 3. The function of these springs is to retract 90 and equalize the rotary movement of the post 8.

15 designates a plate resting on the disk 3 and pivotally secured thereto by a pivot-screw 16. This plate is formed with stop-lugs 15^a and an elongated slot 17, through which latter 95 extends the upper end of the pivot-bolt of the disk 3, thus affording said plate a limited lateral vibrating movement without moving the disk.

Pivots secured upon the plate 15 by a 100

screw-pivot 18 is an arm or link 19, having eccentrically pivoted upon its upper surface a small disk 20, from which projects eccentrically a pin 21, the latter extending through the 5 rod 10.

22 designates the operating lever or handle of the device, having a bend or offset 23 adjacent to its outer end to accommodate the handle of the razor, as shown in Fig. 1. This 10 handle 22 is detachably secured to the forward end of the rod 10 by means of a coupling-sleeve 24, secured by a set-screw 25 to the rear end of the handle and formed near its rear end with an L-shaped slot coöperating with a 15 cross-pin 26, extending through the rod 10 to form a bayonet-joint.

A weight 27, having an eye extension 28, is secured upon the sleeve 24 by a set-screw 28^a.

The handle 22 is provided near its outer end 20 with a spring-clip 29, which firmly clamps the razor-blade in position against the handle, as illustrated in Fig. 1.

The hone or sharpening device is of the rectangular shape shown and is yieldingly supported in front of the disk 3 by means best 25 shown in Figs. 8 and 9. The hone is supported in an inclined position with relation to the disk 3, its supporting means comprising end clips or 30 holders 30, embracing the ends of the hone, and 35 each having an outwardly-projecting pivot-lug 31, fitting a bearing-slot 32, formed in the vertical member of an adjustable angle-bracket 33, said brackets being secured at opposite sides of the base and bored to receive 40 adjusting-screws 34 to facilitate the vertical adjustment of the hone-pivots. This manner of suspending the hone permits it to move freely on its pivots, with the result that the edge of the blade being honed is always in 45 proper contact with the surface of the hone. The stone may also be removed or adjusted without removing the bearings.

The operation of the mechanism constructed as thus described will be readily understood. 45 After the razor or other blade is placed in position upon the handle the latter, together with the rod 10, is given a longitudinal thrust against the tension of the coil-spring 11. The connection of the rod 10 with the small disk 50 20 by means of the pin 21 revolves said disk 20 as the rod and handle are moved laterally. This lateral movement of the rod is permitted by the pivotal movement of the arm or link 19 and plate 15. The movement of the arm 55 5 or link 19 upon the plate 15 is limited by the lugs 15^a, and when said arm strikes one or the other of said lugs the lateral strain is imparted to the plate 15 and through the intermediacy of said plate to the disk 3, causing the latter 60 to partly turn on its pivot. Thus the movement of the operating-handle, aided by the action of the coil-springs employed, is a gyratory movement, which causes the edge of the blade to describe an elliptical curve in its 65 travel over the sharpening-surface.

An important result of the construction and relative arrangement of the mechanism is that all portions of the hone-surface are brought into contact with the edge of the blade during the manipulation of the handle or operating-lever, and it will be apparent that the blade may be readily reversed without detaching the operating-handle from the rod. 70

A distinguishing characteristic of the invention is that it avoids the employment of 75 gearing, belts, and crank-handles, the operation of the handle carrying the blade simulating the ordinary hand manipulation of a razor and accomplishing the same result, but in much less time, much more accurately, and 80 with appreciably less labor.

It will be apparent that when the razor is in position upon the handle 22 the back and edge of the razor will bear on the stone at the same time and the handle not come in contact 85 with the surface of the stone at any point. It will also be apparent that the handle 22 cannot be accidentally disconnected from the rod, as the blade will prevent the turning of the handle to the position required for the separation of the handle and rod, and the blade must first be removed before they can be separated. 90

In the modification shown in Figs. 10 and 11 the handle 22^a is straight and the spring-clip 29^a to receive the razor-blade is located 95 near the rear end of the handle, these variations in structure being necessary to adapt the device for supporting and sharpening the short blade of the so-called "safety-razor." 100

I would have it understood that the invention includes, in addition to the construction illustrated in the drawings, all such modifications and changes in the details as may fall within the scope of the invention as defined 105 by the claims.

Having thus fully described my invention, what I claim as new, and desire to secure by Letters Patent of the United States, is—

1. In a device for sharpening edged tools, the combination with a hone, a base, of a disk pivoted centrally to said base, means limiting the movement of said disk to a partial turn about its pivot, an operating-handle, and mechanism intermediate said disk and handle for permitting the gyratory movement of the handle over the surface of the hone. 110

2. In a device for sharpening edged tools, the combination with a pivotally-supported hone, of a centrally-pivoted disk, means limiting the movement of said disk to a partial turn about its pivot, an operating-handle, and mechanism intermediate said disk and handle for permitting the gyratory movement of the handle over the surface of the hone. 115

3. In a device for sharpening edged tools, the combination with a base, and a disk pivotally supported thereon, means limiting the movement of said disk to a partial turn about said pivot, of a hone pivotally supported upon 120 130

- the base in an inclined position with relation to the disk, an operating lever or handle adapted to support the blade to be sharpened, and mechanism intermediate the disk and handle for 5 permitting a gyratory movement of the handle over the surface of the hone.
4. In a device for sharpening edged tools, the combination with a supporting-base, of a disk centrally pivoted thereon, a hone, an oscillating post extending through said disk, a rod loosely attached to said post, a handle detachably secured to said rod, and means connecting said rod and disk to permit a partial revolution of the disk.
- 15 5. In a device for sharpening razors, and other edged implements, the combination with a supporting-base, and a disk centrally pivoted thereon, of a hone pivotally suspended upon the base, a spring-controlled oscillating post 20 extending through said disk, a spring-encircled rod extending loosely through said post, a handle detachably secured to said rod, a plate pivotally supported on the disk and connections between said plate and rod comprising 25 an arm or link pivoted to the plate, a small disk eccentrically pivoted to the arm or link, and a pin projecting eccentrically from said small disk.
6. In a device for sharpening edged tools, 30 the combination with a base, and a pivotally-suspended hone, of a disk pivotally supported upon the base, an operating-handle adapted to support the tool to be sharpened, and having a bend or offset near its outer end, and mechanism intermediate the disk and handle for 35 imparting a gyratory movement to the latter.
7. In a device for sharpening edged tools, the combination with a base and a hone suspended thereon, of a disk pivotally supported 40 on the base, an oscillating post extending through the disk, a rod loosely attached to said post, a handle, a controlling device for detachably securing the handle to the rod, comprising a sleeve having a bayonet-slot 45 therein, and a cross-pin in the rod, and means intermediate the disk and rod for insuring a gyratory movement of said handle.
8. In a device for sharpening edged tools, the combination with a base, and a suspended 50 hone, of a disk pivotally supported on said base, an oscillating post extending through the disk,
- a rod extending loosely through the post, a handle detachably secured to the rod, a weighted coupling-sleeve between the rod and handle, and means intermediate the rod and disk for 55 imparting a gyratory motion to said handle.
9. In a device for sharpening edged tools, the combination with a base, and a suspended hone, of a disk pivotally supported on said base, an oscillating post extending through 60 the disk, a rod extending loosely through the post, a handle detachably secured to the rod, a coupling-sleeve between the rod and handle, a weight adjustably secured on said sleeve, and means intermediate the rod and disk for 65 imparting a gyratory motion to said handle.
10. In a device for sharpening edged tools, the combination with a base and a hone suspended thereon, of a disk pivotally supported on said base, an oscillating post extending 70 through the disk, springs on opposite sides of said post, a rod extending loosely through said post, a handle attached to said rod, and mechanism intermediate the disk and rod comprising a plate pivoted to said disk, and having an elongated slot, and upwardly-projecting stop-lugs, an arm pivoted to said plate and a small disk and pin carried by said arm, substantially as described.
11. In a device for sharpening edged tools, 80 the combination with a base and a disk pivotally supported thereon, of a hone pivotally suspended above the base and arranged at an inclination with relation to said disk, an oscillating post extending through said disk, a 85 rod extending loosely through the post, mechanism between the rod and disk for effecting a gyratory movement of the rod, a handle, and means for detachably connecting the rod and handle comprising a coupling-sleeve having an L-shaped slot co-operating with a cross-pin in the rod to permit a reversal of the handle without disconnecting it from the rod, substantially as described.
- In testimony whereof I have signed my name 95 to this specification in the presence of two subscribing witnesses.

GEORGE W. MOSBY.
